UNITED STATES PATENT OFFICE.

BENJAMIN B. VAN DERVEER, OF NEW YORK, N. Y.

BAKING FURNACE AND OVEN.

SPECIFICATION forming part of Letters Patent No. 349,771, dated September 28, 1886.

Application filed March 16, 1886. Serial No. 195,418. (No model.)

To all whom it may concern:

Be it known that I, BENJAMIN BEEKMAN VAN DERVEER, a citizen of the United States, and a resident of New York city, New York, have invented a new and useful Improvement in a Baking Furnace and Oven; and I do hereby declare the following to be a full, clear, and exact description of the same, reference being had to the accompanying drawings, and the letters and figures of reference marked thereon, which form a part of this specification.

The objects of my invention are to secure a more regular circulation and a more even distribution of the heat in the oven; to prevent the products of combustion when they are at their highest point of heat—namely, just as they are escaping from the fire—from coming into contact with the goods when they are first put into the oven; to economize in the amount of heat required by bringing the combustion-chamber as close as possible to the pans and reducing the size of the oven, and preventing the escape of heat through the oven-door; and, lastly, to enable the oven and furnace to be operated more easily and economically and with less danger to the operator and the building.

In the accompanying drawings, Figure 1 is a front elevation of my improved furnace and oven. Fig. 2 is a vertical section on the line *x* *x* of Fig. 1, and Fig. 3 is a horizontal section on the line *y* *y* of Fig. 2.

Similar letters refer to similar parts in the different figures.

35 A is the front vertical wall of the furnace and oven. *a* is a part of this front wall, which is set back, preferably, for quite a distance—say two and a half or three feet—from the general plane of the front wall. In front of this 40 part *a* there is thus left a recess or open space, which is preferably arched at the top.

The combustion-chamber of the furnace is placed immediately behind the wall *a*, below which chamber is the grate *b*. The combustion-chamber is long and narrow. It is long 45 in the direction across the furnace from side to side and narrow in the direction from front to rear, as shown in Fig. 3, and is located under the middle portion of the oven.

50 The doors of the furnace may be arranged, as shown in the drawings, one above the fire

to admit the fuel and the other just above the grate, whereby the fire can be sliced and controlled without injury to the contents of the oven; but the furnace-doors can be arranged 55 in any other manner desired, as the arrangement is no part of my invention.

c is the ash-pit.

Directly above the combustion-chamber is the large open chamber *d* of the oven. In this 60 oven there is a reel serving to support and revolve the baking-pans *e*. These baking-pans are made long in a direction across the oven from side to side and narrow in a direction from front to rear, so as to make the pans and 65 the combustion-chamber correspond in shape and arrangement.

f is the door of the oven, through which the 70 contents of the oven are removed or fresh contents supplied.

g *g* are two flues, one opening into the top 75 back portion and the other into the lower back portion of the oven.

Hitherto in all baking-furnaces having the 80 furnace-doors in front the combustion-chamber has been placed immediately back of the front wall of the furnace and under the front 85 part of the oven. This was considered necessary, because if the combustion-chamber was removed back from the front part of the furnace the fire could not be operated and managed successfully, on account of the length of the doorways or passages leading to it. When 90 the combustion-chamber is placed underneath the front part of the oven, as above described, if the combustion-chamber is open, as in Crum- 95 bie's invention, (shown in Letters Patent No. 340,983,) the products of combustion rise up directly to the door of the oven, and immediately come into contact with the goods just as they are introduced into the oven, and as the 100 products of combustion are then at their highest point of heat the goods are apt to be scorched or burned, or else unevenly and irregularly baked. Moreover, this intense heat pours out of the oven-door into the face of the operator and materially interferes with his work. Great quantities of heat are lost in this way also. In the furnaces where the combustion-chamber is not open the heat is conducted into the oven through flues which absorb large quantities of it and necessitate removing the

fire farther from the oven. Besides this, where flues are employed the heat is introduced into the oven at certain points only, and is therefore unevenly distributed and does not bake 5 the goods uniformly.

In my invention the heat is introduced into the oven from below at about the middle point. It rises directly through the center, and is then deflected down on all sides. The part of the oven 10 into which the goods are first placed is therefore not exposed to the direct draft from the fire, but is more moderately heated. Thus the goods are subjected gradually to a higher and higher heat till they pass directly over the fire. 15 In this way they are prevented from being burned or scorched, and are more thoroughly and evenly baked. Moreover, but little heat escapes directly through the oven-door, and thus heat and fuel are economized and the operator is not interfered with by the escaping 20 heat, and therefore is enabled to work more constantly and for a greater length of time.

I am enabled to so place my combustion-chamber by forming a recess in the lower front 25 part of the furnace. The wall *a* is made of suitable thickness, and in it are the doors opening into the combustion-chamber. By forming this recess I am enabled to accomplish several additional purposes. Less space 30 is required in front of the furnace for its operation, as the two or three feet of the recess can be used for this purpose; hence the furnace requires less room for its construction and manipulation.

35 Great danger is experienced in running the ordinary baking-furnaces, because when such furnaces are being started or fed with fuel the sparks, which are discharged from the furnace-doors in great quantities, are apt to set fire to 40 any surrounding wood-work. By making my covered recess this danger is entirely avoided, as the sparks are confined by the sides and roof of this recess.

45 As my combustion-chamber is placed underneath the middle of the oven, the fire is brought nearer to the goods to be baked, for the revolving pans reach their lowest position just over the middle of the bottom of the oven.

Thus the amount of heat required is reduced 50 to a minimum. To secure a more regular distribution of the heat, the combustion-chamber is made to correspond in shape to the baking-pans, so that as each pan comes down imme-

dately over the fire each part of the pan and its contents has a corresponding part of the fire immediately under it, from which it receives a direct charge of heat, and a similar regularity of distribution of heat is caused in the various parts of the oven; hence the goods are evenly and uniformly baked.

60 By my construction of the oven the baking-chamber is made more nearly round and has less unused space. Again, the doors of the furnace and whatever levers and dampers may be connected with them are sheltered by the walls of the recess, and are less apt to be accidentally moved and displaced. When the flues *g*, or either of them, are opened, the central current of heat that passes up directly from the fire is drawn more toward the back, 70 and farther away from the door of the oven. This may at times be found to be desirable. Either flue can be used without the other, or both can be used together. During the operation of baking the flues are generally closed. 75

In my improved furnace and oven less time is required to start the fire and bring it to a proper condition for baking. This results from the fact that the combustion-chamber, being at the middle of the oven, is directly or almost directly under the flue or flues, and a more direct and stronger draft is thus created, because the products of combustion have a shorter distance to travel through the unconfined space of the baking-chamber. The draft 85 being stronger, the fire can be more quickly brought to the requisite point of heat than where the combustion-chamber is placed below the front part of the oven.

What I claim as new, and desire to secure 90 by Letters Patent, is—

In combination with a reel-oven having its bake-pans long in the direction across the oven from side to side, an open combustion-chamber at the bottom and near the median vertical line of the oven, corresponding in form and arrangement with the baking-pans, and having a wall with doors in front, said wall and doors being in the rear of the plane of the front wall of the oven, substantially as and 95 for the purposes set forth.

BENJAMIN B. VAN DERVEER.
